UNITED STATES PATENT OFFICE.

THOMSON McGOWAN, OF CLEVELAND, OHIO.

JACKET FOR LAMP-CHIMNEYS.

SPECIFICATION forming part of Letters Patent No. 412,406, dated October 8, 1889.

Application filed February 28, 1889. Serial No. 301,544. (No model.)

To all whom it may concern:

Be it known that I, THOMSON McGOWAN, of Cleveland, in the county of Cuyahoga and State of Ohio, have invented certain new and useful Improvements in Jackets for Lamp-Chimneys; and I do hereby declare the following to be a full, clear, and exact description of the invention, such as will enable others skilled in the art to which it pertains to make and use the same.

My invention relates to an improved jacket for lamp-chimneys, in which a transparent or at least translucent jacket is employed, surrounding the chimney and sealed to and at the top and bottom of the chimney to exclude air from outside the chimney to prevent condensation of the products of combustion on the inner surface of the chimney, by reason of which any illuminating-oil may be burned in the lamp without smoking the chimney.

In the accompanying drawings, Figure 1 is a side elevation in section. Figs. 2 and 3 are modifications in vertical section.

A represents a lamp-chimney that in the main may be of any ordinary form—for instance, as shown; and B represents a jacket surrounding the chimney, and sealed or closed at top and bottom of the latter, so as to exclude the air from between the two.

In Fig. 1 the jacket and chimney are shown resting on and supported by a holder C, in common such holder being imperforate between the jacket and chimney and fitting each air-tight. The top of the chimney, as shown, is considerably smaller in diameter than the adjacent section of the jacket, and a collar D is arranged to fill the space between the chimney and jacket. This collar is usually of elastic material, so that no accurate fitting is required to insure tight joints, and the under surface of the collar should be of light color and smooth surface, so as to serve as a reflector to throw the light downward, and at the same time, according to the form thereof, to deflect the light more or less outward.

The jacket is usually but not necessarily of glass. Any suitable material that is trans-

parent, or at least sufficiently translucent, 50 will answer the purpose. The object of the jacket is to exclude the atmosphere from the outside of the chimney, and thereby prevent the condensation of the products of combustion on the inner surface of the chimney, or, 55 in common parlance, to prevent smoking the chimney.

I will state as a matter of fact that with my improved jacket attached to the lamp-chimney I have burned a lamp during sixteen consecutive hours without the chimney showing the slightest signs of smoke, and being apparently as clear as at the commencement of the experiment. Meanwhile the lamp was burning such impure low cheap grade of oil 65 as would in a few moments have badly smoked an ordinarily unprotected chimney.

Various modifications may be employed without departing from the spirit and purpose of my invention. For instance, in Fig. 70 2 the chimney is shown with a broad external flange b at the base thereof that engages the jacket, and the joint may be made tight—for instance, by grinding, cementing, fusing, or other suitable means. In Fig. 3 the upper end of the chimney is shown but little less in size than the adjacent section of the jacket, and the chimney is provided with one or more grooves b' for holding packing, whereby a tight joint with the jacket is insured. 80 It is probable that practical means may be found for making the chimney and jacket integral at the bottom, in which case it would be only necessary to use suitable packing or other means for closing the space between 85 the top of the chimney and jacket.

Good results are attained by closing the air-space between the chimney and jacket at the bottom only to prevent a circulation of air through such space.

What I claim is—

1. The combination, with a lamp-chimney, of a jacket surrounding the chimney leaving an air-space between the two, such space being hermetically sealed at both top and bottom, substantially as set forth.

2. The combination, with a lamp-chimney, of a jacket surrounding the chimney leaving

an air-space between the two, such space being hermetically sealed at the bottom and having a packing-ring between the jacket and chimney at or near the top of the latter for closing such air-space at the top, such packing-ring being adapted to serve as a reflector, substantially as set forth.

In testimony whereof I sign this specification, in the presence of two witnesses, this 18th day of December, 1888.

THOMSON McGOWAN.
